UNITED STATES PATENT OFFICE.

THEODORE JONATHAN RITTER, OF NEW YORK, N. Y., ASSIGNOR OF ONE-HALF TO
HENRY BERG, OF BROOKLYN, NEW YORK.

BLOWER.

1,131,554.

Specification of Letters Patent.

Patented Mar. 9, 1915.

Application filed September 10, 1913. Serial No. 789,035.

To all whom it may concern:

Be it known that I, THEODORE JONATHAN RITTER, a citizen of the United States, residing at New York city, in the county of 5 Kings, State of New York, have invented certain new and useful Improvements in Blowers, of which the following is a clear, full, and exact description.

This invention is an improvement in the 10 multi-blade type of rotary fan, and consists in the combination with a series of narrow, closely set peripheral vanes, of a suitable number of inner vanes having the special angular formation hereinafter described.

15 The invention also relates to the form of the peripheral vanes used in this connection.

The features of construction and their advantages and mode of operation will be described in detail in the following specification.

20 In the accompanying drawings: Figure 1 is a sectional side elevation of a blower embodying my improvements. Fig. 2 is an enlarged detail perspective view of some of the 25 peripheral vanes and adjacent central vane. Fig. 3 is a vertical cross-sectional view, the section being taken on a line 3-3 in Fig. 1. Fig. 4 is an enlarged sectional perspective view of one of the central vanes. Fig. 5 30 is a fragmentary vertical sectional view on a reduced scale, and looking from the right in Fig. 3, illustrating one manner of reinforcing the central vanes, the section being taken just inside the back plate.

35 The rotary member 2 or fan proper comprises a plurality of inner vanes 4 and a series of peripheral vanes 3. Before describing the vanes, it may be explained that they are carried by a shaft (not shown), to which 40 power is applied, the vanes being supported at one side by a disk 6 fixed to the shaft by a hub 6^a and at the other side united by a ring 7. The latter forms the inlet side of the fan rotor, and is adjacent the side of 45 the casing 1 having the intake opening 9, the inner circle of the ring and the said opening being preferably approximately of the same diameter. The disk 6 forms the back or closed side of the fan. These principles of construction are familiar in connection with centrifugal fans, and, as is well known, such an assemblage may be doubled, the disk then being central instead of at one side. The inner vanes are bent or

troughed, being composed, either actually 55 or in effect, of two parts or planes 10 and 11, disposed in angular relation to each other, forming pockets 11^a. The part 11, which may be distinguished as the inner part since as a whole it is nearer the axis of 60 the fan, is preferably arranged in general tangential relation to the shaft or to a circle described about the axis, being thus inclined rearward from its inner edge with respect to the direction of movement (which is the 65 same as saying that from its outer portion inwardly it inclines in the direction of movement.) The outer part 10 is bent forward with respect to the lower part and is disposed obliquely between the sides 6 and 7, 70 extending rearwardly with respect to the direction of movement from the inlet side to the back side, as represented in Fig. 2. The vane as a whole partakes of this crosswise bias; the outer or peripheral edge of the 75 part 10 rakes sharply rearward; and the inner edge of the part 11 (the edge nearest the shaft) is also diagonalized in the same direction, though to a less extent. As is apparent from Fig. 1, the bias arrangement 80 of the vanes is such that they overlap each other, the forward portion of each vane (at the inlet side) being in advance of the rear portion of the vane next in front.

It is to be noted that the valley or angle 85 between the parts 10 and 11, at the forward face of the vane extends in a diagonal direction from the inner portion of the vane, at or adjacent the inlet side, outward toward the periphery and toward the back or disk 90 side 6, and also rearwardly with respect to the direction of movement.

In its preferred form the vane is composed of two substantially triangular planes. The parts 11 are widest near their inner 95 portions and narrow outwardly whereas the parts 10 are widest at the periphery and narrow inwardly. Two sides of the triangle 10 form the outer edge and the inlet edge 16^a of the vane, while two 100 sides of the truncated triangle 11 form the inner edge and the back edge of the vane. The inlet edges 16^a of the vanes extend across the intake and all lie in a substantially vertical plane perpendicular to the 105 axis of the rotor. These edges may bear reinforcing strips 13 by which the vanes are bolted to the ring 7, while the back side

edges have flanges 12 bolted or riveted to the disk 6. Between these side members 6 and 7 both parts of the inner vanes are included.

In operation the air is caused to enter as indicated by the arrows 15 between the inlet edges 16^a of the vanes, the two parts of which coöperate in an effective manner to force the air from the central region of the fan outward to the peripheral vanes 3. By reason of the formation and general rearward rake of the central vanes, transversely of the fan, escape of air through the inlet and the production of back draft or eddy currents are avoided or minimized, and the vane action as a whole is rendered more effective.

A further feature of the invention resides in the formation and disposition of the peripheral vanes 3 which consist of a curved outer portion 19 and a portion 20 tangential thereto and to the shaft. The tangential portion of the vanes 20 wedges the air outward while the curved or cup portion 19 carries the air around and drives it out in the usual manner.

The angularity of the portion 20 of the vanes 3 is dependent upon the speed of the blower, the higher the speed the greater will be the angle of the said portion.

The diagonal arrangement of the inner vanes 4 is such as to cause each of these vanes to take in a plurality of the peripheral vanes, and the air is delivered from the pockets 11^a to the ports between the portions 20 of the peripheral vanes.

In a divisional application filed March 27, 1914, Serial Number 827,561, I disclose a fan composed entirely of vanes on the order of the central vanes of the present case, and in that application are included the broad claims to vanes of this character. The claims of the present case are directed

to the combination of the central and peripheral vanes, and it therefore follows that the divisional application is the generic case as to the angular vanes.

I claim as my invention:

1. A rotary fan member comprising a series of adjacent generally parallel peripheral vanes, and a smaller number of central vanes each disposed diagonally so as to take in a plurality of the peripheral vanes and being of angular formation presenting a valley extending diagonally from its inner portion at the intake side to its outer portion at the closed side of the fan, the end of the valley which is toward the intake side of the fan being located in advance of the opposite end as regards the direction of rotation.

2. A rotary fan member comprising a series of adjacent generally parallel peripheral vanes, said peripheral vanes having substantially flat, tangentially disposed inner portions and curved outer portions, and a smaller number of central vanes each disposed diagonally so as to extend across the tangential inner portions of a plurality of the peripheral vanes and being of angular formation presenting a valley extending diagonally from its inner portion at the intake side to its outer portion at the closed side of the fan, the end of the valley which is toward the intake side of the fan being located in advance of the opposite end as regards the direction of rotation.

Signed at Ilion, N. Y., this 8th day of September, one thousand nine hundred and thirteen.

THEODORE JONATHAN RITTER.
